Patented Oct. 11, 1910.

UNITED STATES PATENT OFFICE.

WILLIAM C. HELLER, OF MONTPELIER, OHIO, ASSIGNOR TO THE W. C. HELLER & CO.
-INC., OF MONTPELIER, OHIO, A CORPORATION OF NEW JERSEY.

BOX.

972,449.

Specification of Letters Patent. Patented Oct. 11, 1910.

Application filed June 22, 1910. Serial No. 568,375.

To all whom it may concern:

Be it known that I, WILLIAM C. HELLER, citizen of the United States, residing at Montpelier, in the county of Williams and

5 State of Ohio, have invented certain new and useful Improvements in Boxes, of which the following is a specification.

This invention comprehends certain new and useful improvements in boxes or drawers designed for use in stores, to hold merchandise, the present embodiment of the invention being designed particularly for use in connection with hardware specialties, and the invention has for its primary object a 15 simple, and strong construction of box of this character which will be well built to withstand the comparatively rough use to which it is subjected which will be light and easy to handle and which will at all times retain its original shape, liability to warp being practically precluded.

With this and other objects in view, the invention consists in certain constructions, arrangements and combinations of the parts 25 that I shall hereinafter fully describe and claim.

For a full understanding of the invention, reference is to be had to the following description and accompanying drawings in 30 which:

Figure 1 is a perspective view of a box or drawer constructed in accordance with my invention; Fig. 2 is a perspective view of one corner of the box; Fig. 3 is a top plan view thereof; Fig. 4 is a fragmentary perspective view illustrating the parts which together make up a joint at the corner; and, Fig. 5 is a longitudinal sectional view illustrating a modification hereinafter specifically referred to.

Corresponding and like parts are referred to in the following description and accompanying drawings by the same reference characters.

45 The bottom and sides 2 of my improved box or drawer are integrally formed of a single sheet of metal beat to the required shape and rigidly connected to the preferably wooden front 3 and back 4.

50 In the preferred construction of the parts, kerfs 5 are formed in the side and bottom edges of the front 3 and back 4 to receive the flanges 6 that are formed at the ends of the sheet metal bottom 1 and the sides 2, the 55 edges of the front and back being preferably

scarfed for a depth equal to the thickness of the metal, whereby the side and bottom edges of the parts will lie perfectly smooth and flush with each other.

In the preferred method of construction, 60 the blank out of which the bottom and sides are formed has its corners cut off obliquely by a straight cut so that when the flanges 6 are forced into the kerfs 5, the ends of the sides 2 at the upper edges thereof will present to the wood an oblique edge which will act like a knife in cutting into the top edge of the front 3 and back 4, so that the in-turned top flanges 7 of the sides will lie absolutely flush with the upper edges of the 70 front 3 and back 4. Hence it will be seen that a perfectly flat and smooth top edge is formed all around the box, whereby one box may be easily supported upon a similar box, and slipped in and out at will without any 75 interference. Furthermore, the inturned top flanges 7 obviously serve to reinforce the sides 2, and do not permit any warping or the like.

If desired, one or more sheet metal partitions 9 may be provided, said partitions being preferably beaded and crimped at their upper edges as indicated at 10 so as to avoid the formation of a rough metal edge, the partitions being also flanged at their lower 85 edges as at 11 to reinforce them.

As best seen in Fig. 1, one side 2 is formed with a depressed panel 12 which is preferably enameled so that it may have written thereon the cost and selling price, and the 90 character of the goods contained within the box.

It is to be understood that my invention is not limited to the exact construction and arrangement of parts herein described and 95 illustrated, but that changes may be made without departing from the scope of the invention as defined in the appended claims. For instance, as indicated in Fig. 5, the front of the box may be formed with an upwardly extending lip 3^a substantially equal in height to the thickness of the shelf for which the box is designed. By this means, when a plurality of such boxes or drawers are nested one above the other in their respective compartments, the shelves will be hidden and a substantially unbroken front presented in shelving the goods which will add to the attractiveness of the fixture.

As best illustrated in Fig. 4, it will be 110

2
noted that the inturned top flanges 7 of the sides 2 are inwardly returned upon themselves as indicated at 7^a, the returned portions being formed with oblique end edges 5 7^b. It is these end edges which cut into the side edges of the front 3 and back 4, when the flanges 6 are driven into the kerfs 5, so as to assist in securing the parts rigidly together, providing that the flanges 7 shall lie 10 perfectly flush with the top edge of the front and back.

Having thus described the invention, what is claimed as new is:

A box consisting of a sheet metal bottom 15 and sides, a wooden front and back formed

on their edges with kerfs, the sides and bottom being formed with inturned flanges embedded in the kerfs, and the sides being further formed with top flanges returned inwardly upon themselves with angular ends 20 adapted to shear into the top surface of the wood of the front and back as the first named flanges are forced into the kerfs.

In testimony whereof, I affix my signature in presence of two witnesses.

WILLIAM C. HELLER. [L. S.]

Witnesses:

W. N. Woodson,
FREDERICK S. STITT.
